UNITED STATES PATENT OFFICE.

JASPER M. ROWLAND, OF NIAGARA FALLS, NEW YORK, ASSIGNOR TO HOOKER ELECTROCHEMICAL COMPANY, OF NEW YORK, N. Y., A CORPORATION OF NEW YORK.

TRANSPORTABLE MURIATIC-ACID TANK.

Application filed February 4, 1922. Serial No. 534,200.

To all whom it may concern:

Be it known that I, JASPER M. ROWLAND, a citizen of the United States, residing at Niagara Falls, in the county of Niagara and State of New York, have invented certain new and useful Improvements in Transportable Muriatic-Acid Tanks, of which the following is a specification.

This invention relates to transportable acid tanks.

It has long been known that satisfactory containers for the quiescent storage of muriatic acid (hydrochloric acid solution) can be made by lining wooden tanks or cisterns with pure Pará sheet rubber. The desirability of similar containers for transportation purposes, as railway tank cars or the like, has long been recognized; and many efforts have been made in the past to accomplish this result, but such efforts have not attained any considerable measure of success. The object of this invention is to provide a cheap and durable muriatic acid container of the transportable type.

It has been attempted heretofore, for example, to line cylindrical wooden tanks, horizontally mounted on a railway truck, with pure Pará sheet: but in such cases it has been found that the lining will drop away from the walls, and these efforts have been abandoned. I have found that the failure is attributable, mainly at least, to the penetration from the outside of acid accidentally spilled on the upper portion of the tank, with consequent attack upon the means or devices used for causing the sheet to adhere to the walls. Once the acid has entered between the rubber sheet and the wall of the tank it will quickly penetrate even to remote parts, bringing about a general loosening of the lining.

Among the other efforts to accomplish a similar result the following may be mentioned: Cylindrical wooden tanks, laid horizontally, have been provided with rubber-covered ends, the cylindrical portion being lined with pitch or mastic; steel tanks have been provided with hard rubber linings vulcanized in place, steel tanks have been pro-

vided with interior linings of wood with provision of an innerspace to be filled with pitch or mastic. As already stated, however, none of these constructions have proven able to withstand the conditions of use.

According to the present invention, these difficulties are avoided and a cheap and durable transportable container is made, by constructing the tank, whether cylindrical or rectangular, of two portions which may for convenience be termed a body portion or container and a cover portion or closure. The body portion is lined with pure Pará sheet rubber or unvulcanized rubber in general, as in the case with the stationary storage tanks mentioned above: but this sheet lining is carried over the upper edges of the body and for a sufficient distance down the outside to provide a drip to carry off any accidentally spilled acid flooding down from the cover. This lining may be bonded or cemented to the walls of the tank in various ways, for instance, by attaching a rubber sized cloth lining uniformly in place, and then securing the Pará sheet to the cloth. The cover, which should preferably be sufficiently large to project outwardly from the tank walls on all sides, may be secured in place in any suitable way providing a tight closure, preferably by the use of appropriate gaskets and retaining devices as more fully described below. It is not absolutely necessary that the cover should be rubber lined, although if of material subject to corrosion by the acid it should of course be properly protected, both internally and externally, as by sheet rubber, or by any of the known acid-proof materials, pitch, mastic, etc.

Certain preferred embodiments of the invention are illustrated in the accompanying drawings, wherein

Fig. 1 is a sectional view of an acid tank embodying the invention;

Fig. 2 is a fragmentary sectional view showing a modification of a detail, and

Fig. 3 is a fragmentary sectional view of another modification.

While the tank 10 may be constructed of different materials and may be built in dif-

ferent ways, the walls are preferably built up of straight strips 11 of sound wood which are interconnected at the corners to make the usual dovetail joint and are drawn together by bolts 12 and nuts 13.

The sheet rubber lining 14 is uniformly applied to the bottom and the walls of the tank and passes over the edge sufficiently far to form an overhang or drip 15.

- 10 The cover 16 is preferably provided with a plurality of manholes 17 normally closed by covers 18. An advantageous construction of the manholes comprises seats 19 secured to the cover by means of bolts 20. In these 15 seats are anchored bolts 21 for tightly closing the covers 18 upon the seats.

The cover 16 preferably extends beyond the sides of the tank so that acid spilled upon it will drip clear of the tank.

- 20 While a lining for the cover 16 is not absolutely necessary, I prefer to provide a lining 22 which also extends upwardly through the manholes and over the upper surfaces of the seats 19. The covers 18 are also preferably lined to produce substantially acid-proof joints.

Between the cover and the tank I may provide two gaskets 23 of cured rubber which prevent the sticking of the rubber linings 14 30 and 22 to each other, the parting taking place between the two gaskets.

In order to avoid the expense of the cured rubber gaskets of large dimensions, two layers of fabric such as cloth or canvas 35 may be used instead. In this case, however, a Pará rubber sealing strip 24 (Fig. 2) may be applied to the cover and the tank, the bond being effected by cleaning the sheet rubber surface with gasoline or benzene and pressing them firmly together with an iron roller.

Instead of applying a sealing strip 24, which necessitates the provision of a man-hole to allow a man to enter the tank and 45 work from the inside after the cover is in place, I prefer a seal on the outside of the tank. As shown in Fig. 3 the portion 22^a of the cover lining 22 may be folded down over the overhanging portion 15^a of the tank lining 14 and rolled to a tight joint therewith. The portion 22^a may be held loosely in place on the cover by tacking until the cover is in place.

The cover 16 may be firmly secured by 55 means of bars or beams 25 drawn against the top of the cover by means of bolts 26 and nuts 27 in well known manner.

To safeguard the lining of the cover against injury an asphalt coating 28 may 60 be applied to the top of the cover 16 as indicated in Fig. 2. A sloping of the coating will be advantageous inasmuch as it will promote quick and efficient drainage of the acid free of the tank.

65 Acid spilled upon the cover of the tank

will normally run over the edge of the cover and drop free of the tank. In spite of the overhang of the cover, however, some acid will creep inwardly tending to make its way through the joint between the cover 70 and the tank. At the joint it will come into contact with the drip and flow down on it. From the lower end the acid will take the path of least resistance and either drop or flow down the outer surface of the 75 tank rather than to penetrate to any material extent the wood or to creep upwardly behind the drip toward the edge of the tank. It is of course understood that the drip may be extended downwardly far 80 enough to preclude the creeping of the acid to the upper edge of the tank.

Similarly any acid which should find its way through the seal between the cover and the tank must pass over the drip to the 85 lower edge thereof before it can come into contact with a break in the lining or a line of separation.

While the invention has been clearly described, it may be repeated for the sake of clearness, that it is apparently the acid which creeps between the lining and the walls of the tank that causes the destruction of the bond attaching the lining to the tank and the resulting failing of the lining. 95 By the arrangement described the acid is prevented from finding its way to the bonding material.

I claim:

1. An acid container for the transportation of acid of the type in which size and character render its lining susceptible to injury under normal conditions of use, comprising an open-top tank, a sheet rubber lining extending over the upper edge of the tank and a cover holding the lining in position along the said edge.

2. Apparatus according to claim 1 in which the lining extending over the edge terminates in a depending drip portion.

3. Apparatus according to claim 1 in which the cover projects outwardly beyond the edge.

4. Apparatus according to claim 1 in which the cover is provided with a sheet 115 rubber lining and including a seal between the cover and the tank having parts separable along a horizontal plane.

5. A container for acid subject to conditions causing agitation, comprising an open-top tank, an unvulcanized sheet rubber inner lining extending over the upper edge of the tank and terminating in a depending drip portion, a cover provided with a sheet rubber lining, means for securing the cover upon the tank, and a seal between the cover and the tank including a connection between the sheet rubber linings of the tank and the cover of the tank.

6. A container for acid subject to condi- 130

tions causing agitation, comprising an open-top tank, an unvulcanized sheet rubber inner lining extending over the upper edge of the tank and terminating in a depending drip portion, a cover provided with a sheet rubber lining, means for securing the cover upon the tank, a seal between the cover and the tank comprising two gaskets of fabric and a connection between the sheet rubber linings of the tank and the cover inside the tank.

In testimony whereof, I affix my signature.

JASPER M. ROWLAND.
